Des. 223,575
Patented May 9, 1972

223,575

PORABLE SHOWER

Robert D. Veech, 11 Yates Ave., Commack, N.Y. 11725

Filed May 1, 1970, Ser. No. 22,765

Term of patent 14 years

Int. Cl. D23—02

U.S. Cl. D23—57

FIG. 5

FIG. 1

FIG. 2

FIG. 3

FIG. 4

FIG. 6

FIG. 7

FIG. 8

FIG. 1 is a rear elevational view of my portable shower showing my new design;

FIG. 2 is a side elevation;

FIG. 3 is a front elevation;

FIG. 4 is a side elevation showing the side opposite to FIG. 2;

FIG. 5 is a top elevation of the top as shown in FIG. 1;

FIG. 6 is a bottom elevation of the bottom as shown in FIG. 1;

FIG. 7 is an exploded view showing the shower in an open position; and

FIG. 8 is a perspective view of the right hand portion of the view of FIG. 7 showing the shower in an operative position.

I claim:

The ornamental design for a portable shower, substantially as shown.
